Primary Examiner — Cynthia Ramirez*Assistant Examiner* — Xavier Marti-Santos(74) *Attorney, Agent, or Firm* — Dragon Sun Law Firm, PC; Jinggao Li, Esq.(57) **CLAIM**

The ornamental design for a hair curler, as shown and described.

DESCRIPTION

FIG. 1 is a perspective view of a hair curler showing my new design;

FIG. 2 is a front view thereof;

FIG. 3 is a rear view thereof;

FIG. 4 is a left side view thereof;

FIG. 5 is a right side view thereof;

FIG. 6 is an enlarged top plan view thereof;

FIG. 7 is an enlarged bottom plan view thereof;

FIG. 8 is an enlarged view of a portion of FIG. 2;

FIG. 9 is another enlarged view of a portion of FIG. 2;

FIG. 10 is an enlarged view of a portion of FIG. 4; and,

FIG. 11 is another enlarged view of a portion of FIG. 4.

The broken lines in the drawings illustrate portions of the hair curler and form no part of the claimed design. The additional broken lines demarcating enlarged areas form no part of the claimed design.

1 Claim, 11 Drawing Sheets(56)
